UNITED STATES PATENT OFFICE.

SAM KARPAL, OF HOLMESBURG, PENNSYLVANIA, ASSIGNOR OF ONE-HALF TO JOHN ZACH, OF PHILADELPHIA, PENNSYLVANIA.

FILE CUTTER.

Application filed October 19, 1922. Serial No. 595,577.

To all whom it may concern:

Be it known that I, SAM KARPAL, a subject of the King of Italy, residing at Holmesburg, in the county of Philadelphia and 5 State of Pennsylvania, have invented certain new and useful Improvements in File Cutters, of which the following is a specification.

This invention relates to certain new and 10 useful improvements in file cutters and embodies a machine for cutting the ridges or teeth in the opposite faces of the file blanks.

The primary object of the invention resides in the provision of a file cutting machine wherein a file blank that is perpendicularly supported is adapted to be slowly 15 moved upwardly and struck upon opposite faces thereof by cutting members for forming the file teeth thereon.

Another object of the invention is to provide a novel type of support for the lower 20 end of the file blank, the support being associated with a worm shaft to be moved upwardly thereby, means being associated with 25 said support for frictionally holding the same into engagement with the worm shaft and capable of operation to permit this association between the support and worm shaft and to permit manual vertical shifting 30 of said support.

A still further object of the invention is to provide laterally adjustable supporting frames for the file cutters, said file cutters being resiliently mounted in their support 35 and capable of adjustment for varying the tension thereon and also the striking force thereof.

With the above and other objects in view, the invention consists of the novel form, combination and arrangement of parts herein- 40 after more fully described, shown in the accompanying drawings and claimed.

In the drawings, wherein like reference characters designate corresponding parts 45 throughout the several views,

Figure 1 is a vertical side elevational view of a file cutting machine constructed in accordance with the present invention showing the worm shaft operating the support for the file blank, the tension devices for holding the support in engagement with the worm shaft, and the laterally adjustable file cutter,

Figure 2 is a fragmentary top plan view

of the machine showing the laterally adjustable support for the file cutters and the resilient mounting for the file cutters,

Figure 3 is a horizontal sectional view taken on line III—III of Fig. 1 with the base frame omitted,

Figure 4 is a horizontal sectional view taken on line IV—IV of Fig. 1 showing the file support and the wind shaft for elevating the same,

Figure 5 is a detail sectional view taken on line V—V of Fig. 1 showing the striker arm on the cross shaft for retracting the file cutter against the spring tension thereon and the adjustable mounting for the file cutter support.

Figure 6 is a detail sectional view of a portion of the wind shaft and file support, and

Figure 7 is a detail sectional view taken on line VII—VII of Fig. 6.

Referring more in detail to the accompanying drawings, there is illustrated a file cutting machine embodying a frame having a base supporting stand 1, preferably of rectangular formation in plan view as illustrated in Fig. 1, the file cutting and other mechanism being supported upon the base 1.

A frame structure mounted on the base support 1 embodies perpendicular end bars 2 and spaced intermediate perpendicular bars 3 and 4, the bar 4 being vertically slotted as shown in Fig. 4 with rack teeth 4^a provided on the opposite vertical walls of said slot. A cross brace 5 connects the perpendicular bars 2, 3 and 4 adjacent the lower ends thereof while oppositely extending horizontal arm sections 6 respectively connect the intermediate perpendicular bars 3 and 4 to the adjacent end bars 2 as clearly shown in Fig. 1.

The file support and mechanism for elevating the same embodies a horizontal power shaft 7 journaled through one of the end bars 2 as at 8, and further journaled in standards 9 and 10, has a loose pulley 11 and a fixed pulley 12 associated therewith. A perpendicular shaft 13 journaled in bearings 14 between the perpendicular bars 2 and 3 has a worm portion 15 disposed between the cross braces 5 and the adjacent upper arm section 6, the lower end of the worm 15 carrying a fixed pinion 16 that meshes with a pinion 17 upon the adjacent end of the power shaft 7. The support for the file

2
blank F embodies a block 18 having a socket 18^a at the upper side thereof for supporting the lower end of the file F, the supporting block 18 being positioned between the intermediate perpendicular bars 3 and 4 and being formed integral with the rectangular frame 19 that incloses the bar 3. As shown more clearly in Figs. 1, 6 and 7 an arm 20 carried by the rectangular frame 19 and extending laterally thereof has a head 21 swiveled thereto as at 22, the head carrying a projecting pin 23 that extends into the grooves of the spiral gear 15. The support for the opposite end of the block 18 embodies a relatively short cylinder 24 that rotatably receives the projecting pin 25 from the file supporting block 18, the cylinder 24 being provided with peripheral gear teeth 26 that mesh with the rack teeth 4^a upon one wall 20 of the slot formed in the perpendicular bar 4. It will therefore be seen that upon rotation of the power shaft 7, the worm 15 is rotated and the connections above described between said worm and the file supporting block 18 will effect a vertically shifting movement of said block with the file F supported therein.

In order to maintain operative connections between the pins 23 carried by the frame arm 20 and the worm 15, a perpendicular arm 27 having angularly bent ends 28 positioned between spaced guide flanges 29 carried by the cross brace 5 and the arm section 6 at that side of the machine frame opposite the worm 15. A coil spring 30 is interposed between each end of the arm 27 and the bar 4 as shown in Fig. 1 that tend to move the arm 27 laterally of the machine frame for disengagement with the adjacent end of the cylinder 24 associated with the file supporting block 18. A shaft 31 swiveled at one end in the arm 32 is threaded through a bearing 33 carried by the perpendicular end bar 2 and provided upon the outer end thereof with a hand wheel 34, axial inward movement of the shaft 31 moving the arm 27 against the tension of the springs 30 for frictionally engaging the cylinder 24 to shift the file supporting block 18 and arm 20 to move the pin 23 into engagement with the groove in the worm 15. A lever rod 35 extends through the rectangular frame 19 of the file supporting mechanism and is pivoted at its lower end as at 36 to the cross brace 5, the upper end thereof being engaged by the spring 37 that cooperates with the lug 38 carried by the adjacent arm section 6 that normally tends to move the upper end of the lever rod 35 away from the intermediate bar 3 for engagement with the rectangular frame 19 as shown in Fig. 4 for laterally shifting the file supporting block 18 to disengage the supporting block from the worm 15.

65 A frame structure is disposed above the

file blank elevating mechanism and embodies a cross head 39 carried by the upper end of each perpendicular end bar 2, the cross heads 39 being connected by horizontal side rails 40 spaced inwardly of the opposite ends of said cross head, while a shaft 41 is journaled in the ends of said cross head at the outer side of each connecting rail 40, the shafts 41 having spaced oppositely threaded portions 41^a. As shown in Figs. 2 and 3, a gear wheel 42 is secured to adjacent ends of said shafts 41, while a stub shaft 43 journaled in the adjacent cross head 39 carries a gear 44 meshing with the gears 42 and operable by a hand wheel 45. A support for a file cutter is associated with the oppositely threaded portion 41^a of the shaft 41 at each side of the machine frame, said support including perpendicular legs 46 carrying lateral extension arms 47 at the lower ends thereof with a depending lug 48 carried by the outer end of each extension 47 provided with a threaded opening to receive the threaded portion 41^a of said shaft. The outwardly positioned leg 46 being of greater height than the inwardly positioned leg, affords the inclined mounting of a file cutter guide 49 provided with inclined side guard flanges 50, a file cutter blade 51 flatly resting upon the guide 49 and properly retained in position thereon by the hinge 52 passing through said guard flanges and overlying the cutter blade as clearly shown in Figs. 2 and 5. A cross bar 53 extending between the side rails 40 is provided with a central opening surrounded by a guide flange 54 for the file blank F, the upper end of the file blank extending between the adjacent ends of the cutter blades 51 as shown in Fig. 1, while guard fingers 55 adjustably carried by bracket extensions 56 supported by the inclined guides 49 insure the centering of the file blank between the cutter blades. Each cutter blade is provided adjacent the outer end thereof with an upstanding lug 57 and a pin extension 58 that is surrounded by a coil spring 59. A bracket arm 60 carried by the outer end of each guide 49 adjustably supports an apertured screw plug 61 through which the cutter blade pin 58 extends, the screw plug 61 engaging the outer end of the coil spring 59 for varying the tension thereof to control the striking force upon the file blank S.

The operating mechanism for the cutter blades 51 embodies four perpendicularly extending rods 62 supported upon the base stand 1 with a cross shaft 63 journaled in the upper ends thereof above the blade guides 49 as shown in Figs. 1 and 2. A finger 64 is carried by each shaft 63 and upon rotation of said shaft is adapted to be moved into engagement with the cutter blade lug 57 for retracting the cutter blade against

the tension of the spring 58. One of the shafts 63 is provided with an end pulley 65 driven by a belt 66 from a suitable source of power, while the shafts 63 are connected by a cross belt 67 passing over pulleys 68.

From the above detail description of the device, it is believed that the construction and operation thereof will at once be apparent, it being understood that when the supporting block 18 is in its lowered position, a file blank S is mounted therein as illustrated in Fig. 1. By rotating the shaft 31 by the hand wheel 34, the arm 27 is moved into friction engagement with the cylinder 24 of the block mechanism, against the tension of the springs 30 for operatively connecting the block 18 to the worm 15 as shown in Figs. 1, 6 and 7. The file cutter guides 49 are transversely shiftable upon the screw 20 shaft 41 for properly positioning the same relative to the upper end of the file F. Power applied to the shaft 7 will rotate the worm 15 and thereby elevate the block 18 supporting the file blank. Power applied to 25 the pulley 65 will rotate the shaft 63 and cause the fingers 64 carried thereby to engage the cutter blade lugs 57 to retract the same against the tension of the springs 58 and when said fingers escape the lugs, the 30 springs 58 forcibly return the cutting edges of said blade into engagement with the upper end of the file blank, it being understood that the blades 51 may be angularly disposed as indicated in Fig. 2 for cutting the 35 proper form of tooth upon the file blade. The tension of the spring 59 is regulated by the screw plugs 61 for controlling the striking force of the cutter blades relative to the file blank. The power devices for the shaft 40 7 and the shaft 63 are so timed as to permit a continuous cutting operation upon the file blank with each tooth of the file blank evenly spaced. In removing the completed file from the machine, and when the file supporting block 18 is in its limit of upward movement, the shaft 31 is reversely rotated to permit the springs 30 to displace the arm 27 from frictional engagement with the adjacent end of the block cylinder 24, at 45 which time the tensioned arm 35 engaging the rectangular frame 19 of the block supporting mechanism will shift said frame and block to disconnect the same from the worm 15, the block 18 then being lowered 50 while the cylinder 24 revolves upon the end 25 of said block in passing over the rack teeth 4^a on the frame bar 4.

While there is herein shown and described the preferred embodiment of the present invention, it is nevertheless to be understood that minor changes may be made therein without departing from the spirit and scope of the invention as claimed.

What I claim is:

1. In a file cutting machine, a frame struc-

ture including a plurality of perpendicular guide bars, a power operated perpendicular worm shaft journaled in the frame structure, a vertically shiftable file blank supporting block guided by the frame bars 70 and capable of limited lateral movement, a rectangular frame carried by said block enclosing one of the frame bars, an arm carried by said rectangular frame and having a swiveled head associated with the worm shaft, a cylinder rotatably supporting the opposite side of said block, a rack and gear connection between said cylinder and an adjacent frame bar, a screw adjusted plate engaging the cylinder for moving the swiveled head 75 into engagement with the worm shaft, and file cutting means associated with the upper end of the frame structure.

2. In a file cutting machine, a frame structure including a plurality of perpendicular guide bars, a power operated perpendicular worm shaft journaled in the frame structure, a vertically shiftable file blank supporting block guided by the frame bars and capable of limited lateral movement, a rectangular frame carried by said block enclosing one of the frame bars, an arm carried by said rectangular frame and having a swiveled head associated with the worm shaft, a cylinder rotatably supporting 80 the opposite side of said block, a rack and gear connection between said cylinder and an adjacent frame bar, a screw adjustable plate engaging the cylinder for moving the swiveled head into engagement with the worm shaft, file cutting means associated with the upper end of the frame structure, and a tensioned lever arm extending through the rectangular frame adapted to shift the same and the file blank supporting block 85 90 to disengage the swiveled head from the worm shaft when the screw operated plate is displaced from engagement with said cylinder.

3. In a file cutting machine, a frame structure, a file blank supporting block vertically shiftable in the frame structure, laterally adjustable cutter blade supporting guides associated with the upper end of the frame structure, said guides including screw 110 shafts journaled upon the frame structure for supporting the guides, a cutter blade resiliently mounted in each guide, a projecting lug carried by each cutter blade, and striker means associated with the cutter blade lug for retracting the same against the spring tension thereon and subsequently disengaged therefrom to permit tensioned movement of the cutter blades in directions toward the file blank.

4. In a file cutting machine, a frame structure, a file blank supporting block vertically shiftable in the frame structure, laterally adjustable cutter blade supporting guides associated with the upper end of the 115 120 125 130

frame structure, said guides including screw shafts journaled upon the frame structure for supporting the guides, a cutter blade resiliently mounted in each guide, a projecting lug carried by each cutter blade, and striker means associated with the cutter blade lug for retracting the same against the spring

10 tension thereon and subsequently disengaged therefrom to permit tensioned movement of the cutter blades in directions toward the file blank, and means for varying the tension on the cutter blades.

In testimony whereof I affix my signature.

SAM KARPAL.
